MAGNETIC SOAP BAR HOLDER

Jan Jarema, 3360 E. 76th St.,
Cleveland, Ohio 44127

Filed Mar. 12, 1969, Ser. No. 16,206

Term of patent 14 years

Int. Cl. D6—01

U.S. Cl. D33—25

Fig. 1

Fig. 2

Fig. 3

Fig. 4

Fig. 5

Fig. 6

FIG. 1 is a rear elevational view of a magnetic soap bar holder embodying my new design;

FIG. 2 is an elevational view taken from one side thereof;

FIG. 3 is a bottom plan view thereof;

FIG. 4 is a top plan view thereof;

FIG. 5 is a front elevational view thereof; and

FIG. 6 is a cross-sectional view, taken on the line 6—6 of FIG. 3.

I claim:

The ornamental design for a magnetic soap bar holder, substantially as shown.
